UNITED STATES PATENT OFFICE.

SAMUEL OAKMAN, OF MELROSE, MASSACHUSETTS.

BASKET-SPLINT MACHINE.

SPECIFICATION forming part of Letters Patent No. 292,942, dated February 5, 1884.

Application filed November 19, 1883. (No model.)

To all whom it may concern:

Be it known that I, SAMUEL OAKMAN, of Melrose, in the county of Middlesex and State of Massachusetts, have invented certain new and useful Improvements in the Art of Making Wood Splints for Wicker-Work, of which the following is a specification.

My invention relates to making by machinery thin narrow strips of wood, suitable for use in covering bottles and for general purposes in which strips of rattan are used.

In the accompanying drawings I show the working parts of a machine by which I am enabled to make the wood strips of the desired shape and size; also the article in its progress of being manufactured.

Figure 1 is a perspective view, showing the working parts of the machine for making my wood strips. Fig. 2 shows a piece of thin wood as it is prepared for basket-work, &c. Figs. 3 and 4 represent the shape and appearance of the wood after it has passed under the molding-tool, and Figs. 5 and 6 represent the shape of the completed strip or splint.

25. In Fig. 1, A represents the bed of the machine; B B', the feeding-in rolls; C, the cutter-head; D D', the drawing-rolls.

E is a roll which runs in contact with the points of the knives F, and serves, in connec-

tion with the knives F, to cut the molded 30 wood (see Figs. 3 and 4) into the strips, as shown in Figs. 5 and 6.

H, Fig. 1, represents an opening through which the finished strips pass. The object of this is simply to keep the finished strips from spreading and becoming entangled with each other or with the machinery.

The method of making wicker-work splints consists in taking thin riven sheets of wood, such as basket-makers use, (see Fig. 2,) passing it through the molding-machine B B' C D D', and then cutting it into strips suitable for use.

I claim—

In a machine for making wicker-work 45 splints, the combination of the feed-rolls B B', the cutter-head C, whereby the riven wood is formed into a sheet, flat on one side and cut nearly through by corrugations on the other side, with the corrugated feed-roll D, smooth-roll D', pressure-roll E, and series of knives F, all arranged to operate substantially as described, and for the purpose set forth.

SAMUEL OAKMAN.
